No. 653,586.

Patented July 10, 1900.

A. G. NEVILLE.

MACHINE FOR SPREADING BLOWN GLASSWARE.

(Application filed Dec. 5, 1899.)

(No Model.)

UNITED STATES PATENT OFFICE.

ASA G. NEVILLE, OF WELLSBURG, WEST VIRGINIA.

MACHINE FOR SPREADING BLOWN GLASSWARE.

SPECIFICATION forming part of Letters Patent No. 653,586, dated July 10, 1900.

Application filed December 5, 1899. Serial No. 739,296. (No model.)

To all whom it may concern:

Be it known that I, ASA G. NEVILLE, a citizen of the United States, residing at Wellsburg, in the county of Brooke and State of 5 West Virginia, have invented certain new and useful Improvements in Machines for Spreading Blown Glassware; and I do hereby declare the following to be a full, clear, and exact description of the invention, such as will enable 10 others skilled in the art to which it appertains to make and use the same.

This invention relates to glass-finishing machinery of the type designed for spreading blown ware and used chiefly in the manufacture 15 of globes and shades for the many varieties of lamps.

The invention consists, essentially, of a rotary shaft, collars relatively fixed to the shaft, shapers or templets, links connecting 20 opposite ends of the shapers with the said collars, and a runner applied to the shaft and having connection with the shapers to cause an expansion or a contraction thereof, as required.

25 The invention also consists of the novel features, details of construction, and combinations of the parts which hereinafter will be more fully set forth, illustrated, and claimed.

Within the purview of the invention it is 30 contemplated to vary the form, proportion, and minor details of construction of the invention without departing from or sacrificing any of the advantages thereof.

The primary object of the invention is the 35 provision of a machine of the character aforesaid which will involve a simple construction easy of operation and effective for the purpose designed.

In the drawings, Figure 1 is a perspective 40 view of a spreading and forming machine embodying the essential features of the invention. Fig. 2 is a view in elevation, the dotted lines showing the relation of the parts when the article is spread or expanded. Fig. 45 3 is a sectional detail view of the upper portion of the machine.

Corresponding and like parts are referred 50 to in the following description and indicated in all the views of the drawings by the same reference characters.

The working parts of the machine are mounted upon a stand of suitable design

found best adapted for the purpose. As shown, this stand is composed of a base 1 and a corresponding upper plate 2, posts or uprights 3 serving to connect the base and upper plate. The vertical shaft 4 is stepped at its lower end in a block applied to the top side of the base 1 and is journaled in the plate 2 and is provided at its lower end with 55 a band-pulley 5, which receives motion from the shaft 6 by means of an endless drive-belt 7, passing around the pulley 5 and a corresponding pulley 8, secured to the said shaft 6. The shaft 4 projects a considerable distance above the plate 2 in order to receive the spreading device and other connecting mechanisms.

A collar 9 is adjustably connected to the upper end of the shaft 4 and is provided at 70 intervals in its circumferential length with pairs of ears 10, to which the inner or lower ends of links 11 are pivotally connected. A second collar 12 is likewise adjustably connected with the vertical shaft 4 and is provided with pairs of ears 13 at intervals in its periphery, to which the inner or lower ends of links 14 are pivotally attached. The links 11 normally have a parallel relation, as most clearly indicated in Figs. 2 and 3, whereas the 80 links 14 are normally upwardly divergent. Shapers or templets 15 have pivotal connection with the upper outer terminals of the set of links 11 and 14 and normally have an upward divergence, their upper ends being inwardly curved and their lower portions straight. The upper ends of the shapers or templets 15 have pivotal connection with the free ends of the links 11 and their lower ends are pivotally connected with the outer ends 90 of the links 14. The links besides having a different relative angular disposition are of different lengths. Hence the shapers or templets have a differential movement imparted thereto, their lower ends moving more rapidly 95 than their upper ends when the said shapers are operated to expand the article to be shaped. As is well known, the article when blown is hollow, and when detached from the pipe an opening is provided, and this opening is 100 of a size to admit of the lower portion of the article when reheated and placed on the machine receiving the upper ends of the templets or shapers 15, and when the latter are

moved outward at the same time serve to spread or expand the article, as will be readily comprehended and as shown by the dotted lines in Fig. 2.

5 Various means may be resorted to for causing a contraction and expansion of the shaping devices and, as shown, a runner 16 is slidably mounted upon the shaft 4 and is provided with seats or pairs of ears at intervals in its 10 periphery, and these seats receive the lower ends of links 17, which are pivoted thereto, the upper ends of the links having pivotal connection with the lower ends of the tem- 15 plets or shapers 15. A spring 18 of the coil type is mounted upon the shaft 4 and is confined between the plate 2 and the lower end of the runner 16 and exerts an upward thrust 20 against said runner to hold the shaper contracted. A foot-lever 19 is horizontally dis- 25 posed and is pivoted at one end to a bracket 20, attached to the plate 2, and this foot-lever is spread at a central point to embrace the sides of the runner 16, the latter being annularly grooved to make interlocking connection 30 between the runner and lever, whereby when said lever 19 is depressed at its outer end by the application of the foot of the operator thereto the spring 18 is compressed and the runner 16 lowered, thereby causing a spread- 35 ing or expanding of the shaping device and the article applied thereto. When the pressure is removed from the lever 19, the spring 18, previously compressed, regains itself and returns the elements of the shaper to a normal position, as shown.

The shaft 4 is provided at its upper end with a centering device 21, which consists of a pin rounded at its upper end and having an annular flange 22, adapted to form a support 40 in the neck portion of the article when expanded, as shown by dotted lines in Fig. 3. This insures equal expansion or spreading of the article at all points in its circumference and insures the centralizing of the neck or 45 collar. It is to be understood that the shaping devices are rotated when the machine or apparatus is in operation, thereby bringing each element of the mechanism—that is, the shapers or templets 15—into contact, so as to 50 insure like and equal expansion thereof.

The apparatus is especially designed for finishing articles having a flaring form when completed, and is particularly devised for finishing shades for lamps and lights of various 55 kinds. The article when blown and detached from the blowpipe is caught by a post or snap in the well-known manner, and the end de-

tached from the blowpipe is fitted upon the upper or smaller end of the shaping device and is gradually lowered thereon as the expanding or spreading progresses. In this connection it is to be remembered that the shaping devices are rotated at a comparatively-high rate of speed. When the lower end of the article is fitted upon the upper portion of 60 the shaper, the operator presses down upon the outer end of the treadle or foot-lever, thereby spreading the templets or shapers 15 and causing a corresponding expansion of the article fitted thereto.

This machine may be used in conjunction with others and may finish the article or serve simply to give an initial spread thereto, as required.

Having thus described the invention, what 75 is claimed as new is—

1. In apparatus for shaping blown glassware, a vertical rotary shaft, spaced collars applied to said shaft, upwardly-convergent shapers having their upper ends incurved, 80 upper links normally parallel and pivotally connecting the curved extremities of the shapers with the upper collar, lower links upwardly divergent and longer than the upper links and pivotally connecting the lower ends 85 of the shapers with the lower collar, a runner coaxially disposed with reference to the said shaft, other upwardly-divergent links connecting said runner with the lower or divergent ends of the shapers, substantially as 90 set forth.

2. In glass-finishing apparatus of the character described, a vertically-disposed shaft, spaced collars having adjustable connection with said shaft, means for securing said collars positively to the shaft in an adjusted position, shapers grouped about the shaft, links pivotally connecting, respectively, opposite ends of the shapers with the said spaced collars, a runner slidably mounted upon the 100 shaft, links pivotally connecting the runner with the divergent ends of the shapers, a spring exerting a force against the runner to hold the parts in a normal position, means for imparting a rotary movement to the shaft, 105 and a foot-lever for connection with the said runner, as and for the purpose set forth.

In testimony whereof I affix my signature in presence of two witnesses.

ASA G. NEVILLE. [L. S.]
